Des. 185,165
Patented May 12, 1959

185,165

METAL CHAIR FRAME SIDE

Charles P. Molla, Old Westbury, N.Y.

Application April 4, 1958, Serial No. 50,343

Term of patent 14 years

(Cl. D15—1)

Fig. 1 is a side view of a metal chair frame side, showing my new design; and

Fig. 2 is a front view of the frame side, as shown in Fig. 1, the broken lines being shown for illustrative purposes only.

I claim:

The ornamental design for a metal chair frame side, as shown and described.
